ARM CHAIR

John O. Van Koert, New York, N. Y., assignor to Drexel
Furniture Company, Drexel, N. C., a corporation of Delaware

Application August 2, 1955, Serial No. 37,270

Term of patent 7 years

(Cl. D15—1)

Fig. 1.

Fig. 2.

Figure 1 is a perspective view of an arm chair incorporating my new design when viewed from the front; and, Figure 2 is a perspective view thereof as viewed from the rear.

I claim:

The ornamental design for an arm chair, as shown.
